UNITED STATES PATENT OFFICE.

JAMES F. LESTER, OF ATLANTA, GEORGIA.

SMOKE-CONSUMER.

SPECIFICATION forming part of Letters Patent No. 664,485, dated December 25, 1900.

Application filed March 19, 1900. Serial No. 9,323. (No model.)

To all whom it may concern:

Be it known that I, JAMES F. LESTER, a citizen of the United States, residing at Atlanta, in the county of Fulton and State of Georgia, 5 have invented a new and useful Smoke-Consumer, of which the following is a specification.

This invention relates to improvements in smoke-consumers, and more especially to that 10 class wherein the consumer proper is capable of being adjusted to fire-boxes of boilers, furnaces, or any heating medium wherein the gaseous smoke is not entirely consumed.

The prime object and purpose of my invention is to provide an apparatus which may 15 be placed within a fire-box and supported directly over the fire, so as to direct all the products of combustion through a series of super-heated flues wherein a suitable supply of air 20 is admitted and mixed with the product, which action causes the gases eliminating from the fuel to be mixed and ignited.

A further object of my invention is to provide an apparatus having therein an air- 25 chamber from which a series of air-flues lead to respective combustion-product flues, providing thoroughly-heated air to the escaping products and igniting the gases before they escape to the chimney.

30 A further object of my invention is to provide an apparatus which can be adapted to coact with any fire-grate construction, so as to consume all the smoke-gases, in combination with an auxiliary or supplemental combustion-chamber, wherein the heat is disseminated and is directed to perform the function 35 for which it has been created.

A further object of this invention is to provide an apparatus whereby a large proportion 40 of the gases which ordinarily become smoke are caused to ignite before they are converted into this state, and said gases which do become smoke are subjected to a continued mixing action with highly-heated air and are 45 eventually consumed.

A further object of this invention is to provide a heat-absorbing block having therein a series of divergent exit combustion-flues, the smaller ends being adjacent the fire, 50 which allows the molecules of gases after they enter the flues to separate to permit of a ready mixing action of introduced highly-heated air.

Many other objects and advantages will be hereinafter referred to and be particularly pointed out in the claims.

55

In the drawings forming a part of the specification, Figure 1 is a longitudinal section showing the application of my improvement to a tubular boiler of ordinary type. Fig. 2 is a transverse section of the same on the line 60 2 2 of Fig. 1. Fig. 3 is a similar view on the line 3 3 of Fig. 1. Fig. 4 is a perspective view of the complete apparatus detached. Fig. 5 is a sectional view showing a slight modification. Fig. 6 is a sectional view showing a 65 slight modification of the arrangement of the air-flues.

Referring to the drawings, 1 indicates a tubular boiler of any well-known construction, provided with the usual fire-box 2, grate 3, 70 and ash-pit 4.

In the practical application of my invention I prefer to construct the parts about to be described in sections; but for clearness of description and drawing a solid mass is shown 75 having the various flues formed therein.

The numeral 5 represents the heat-absorbing block of my improved smoke-consumer, made up of some refractory material, preferably of a suitable composition of fire-clay 80 and asbestos. This heat-absorbing block 5 is provided with suitable supporting-legs 6, designed to rest directly on the grate-bars 3, and is constructed on its under side and directly over the grate with a preferably con- 85 cave cavity 7. Extending up from and communicating with said concavity are a series of what I shall term "combustion-flues" 7^a, the opposite ends of said flues entering a supplemental combustion-chamber 8, which lat- 90 ter in the showing in the drawings is between the heat-absorbing block 5 and the end of the boiler.

For the sake of more readily directing the products of combustion to the chamber and 95 at the same time preventing as much as possible the overheating of the roof of the heat-absorbing block 5 the flues are curved toward the line of draft and diverge toward the bottom, as at 9, to allow the molecules of smoke 100 and gas to separate and have free movement to better enable the mixing action with the admitted heated air.

Within the upper portion of the heat-ab-

sorbing block 5 is an air-chamber 10, having an inlet 11, regulated by a damper 12, and at its rear it communicates with the supplemental combustion-chamber, as at 13. For 5 the purpose of making this opening distinctive in the description and claims it will be hereinafter referred to as the "main exit-opening 13." Tapered flues 14 connect this air-chamber 8 with the combustion-flues 7^a, 10 one or more of said flues 14 for each of the respective flues 7^a entering the latter at such a point from the main combustion-chamber as will best allow the heated oxygen to thoroughly mingle and mix with the escaping 15 smoke-gas and give it ample time to ignite said gas before it reaches the supplemental combustion-chamber.

From the foregoing it is thought the advantages and operation of the apparatus will be 20 understood. The fire is made, as usual, on the grate, and as the products of combustion must enter the flues 7^a in their exit to the chimney the molecules of gas immediately commence to separate, whereupon the streams 25 of heated air are introduced, and they in turn immediately begin a mixing action with the products of combustion, and by the time the two (now as one) reach the supplemental combustion-chamber all the gases have been 30 ignited and nothing but the heat derived therefrom is directed to where it is needed—for instance, as shown in the drawings—for steam generation.

It will be understood as the fire is continued 35 for awhile the whole apparatus becomes a thoroughly-heated body, and it is this feature, in connection with the arrangement of my flues, that enables me to obtain the desired results. The air within the chamber 40 becomes highly heated and in this condition is introduced to the various flues, when it meets the products with such force as to cause the two to mingle and mix, and the two being in this highly-heated condition the smoke- 45 gases readily ignite. However, should there not be enough air introduced to the respective combustion-flues to ignite all the gases as they pass through such escaping gases will be subjected to and mixed with a highly- 50 heated supply of air introduced into the supplemental combustion-chamber through the main exit-opening 13.

As my improvement can be applied to all 55 sorts of plants using fire where the smoke is not consumed, it will of course be understood that the supplemental combustion-chamber and the exact location of the flues entering therein will have to be directed thereto according to the existing conditions.

60 When my improvement is applied to locomotive-boilers or boilers of horizontal type, it is preferable that the combustion-flues be curved and be of variable lengths. For instance, by the arrangement shown—that is, 65 the flues curved and directed toward the line of draft—a greater velocity of air is obtained,

and the upper part of the heat-absorbing block and the boiler over the fire-box are prevented from becoming so overheated as to render their use impracticable. The variation 70 in size of the combustion-flues is another feature which prevents the overheating of the parts, as above described, and in addition thereto they tend to force the products into many different directions, owing to the variable lengths and their relative positions to the line of draft. This variation induces the air-currents to travel at different velocities, which contact with each other and create a series of resistances, causing the molecules of 80 gas to break, scatter, and be more susceptible to ignition.

I much prefer making the heat-absorbing block of the refractory material heretofore mentioned—i. e., a composition of fire-clay 85 and asbestos. However, any other refractory material may be employed which will withstand the heat and at the same time not become glazed to stop up the flues.

Arranging the parts in such close proximity to the products of combustion enables the gases or a large proportion of them to be ignited before they are converted into smoke, thereby returning them into their elementary condition. This is brought about by the heated air being introduced to meet the gases almost immediately they commence to separate after they have been first broken by entering the combustion-tubes.

In the modified form of my invention as disclosed in Fig. 5 the air is taken into the tubes directly from the atmosphere and is heated in its passage to the combustion-flues. While this construction is desirable under certain circumstances, I much prefer the air to be 105 taken into the flues from a heated chamber, as shown and described. The arrangement of the air-flues may also be different than shown in the preferred form. For instance, the flues 14^a feed a series of combustion-flues 7^a instead of one for each respective flue. This change of introducing the air is susceptible to either the construction shown in Fig. 1 or that shown in Fig. 5.

Having thus described my invention, what 115 I claim, and desire to secure by Letters Patent, is—

1. The combination of a fire-box, and a heat-absorbing block, said block being provided on its under side with a cavity, a series of 120 divergent combustion-flues communicating with said cavity, and means for supplying air thereto, as set forth.

2. The combination of a fire-box, and a heat-absorbing block, said block being provided 125 with a series of divergent combustion-flues, and a series of tapered air-flues for supplying air to the combustion-flues, as set forth.

3. The combination of a fire-box, an air-heating chamber, and a heat-absorbing block, 130 said block being provided with a series of divergent combustion-flues of variable lengths,

and a series of air-inlet flues connecting the air-heating chamber and the combustion-flues, as set forth.

4. The combination of a fire-box, an air-heating chamber, a heat-absorbing block, said block being provided with a series of divergent combustion-flues, and means for supplying air to said combustion-flues from the said heating-chamber, as set forth.

10 5. The combination of a fire-box, a heat-absorbing block, said block being provided with a series of divergent combustion-flues and an air-heating chamber, and flues for supplying air to the combustion-flues from the air-chamber, as set forth.

15 6. The combination of a fire-box, a supplemental combustion-chamber, and a heat-absorbing block, said block being provided on its under side with a cavity, a series of divergent combustion-flues communicating with the cavity and the supplemental combustion-chamber, as set forth.

20 7. The combination of a fire-box, a supplemental combustion-chamber, a heat-absorbing block, said block being provided with a series of divergent combustion-flues communicating with the supplemental combustion-chamber, and means for supplying air to said combustion-flues, as set forth.

25 30 8. The combination of a fire-box, a supplemental combustion-chamber, a heat-absorbing block, said block being provided with a series of divergent combustion-flues communicating with the supplemental combustion-chamber, and an air-heating chamber, means for supplying air to the chamber and means for supplying air to the flues from said chamber, as set forth.

35 40 9. The combination of a fire-box, a supplemental combustion-chamber, means for supplying air to said chamber, a heat-absorbing block, said block being provided with a series of divergent combustion-flues communicating with the supplemental combustion-chamber, and means for supplying air to the combustion-flues from the means for supplying air to the combustion-chamber, as set forth.

45 50 10. The combination of a fire-box, and a heat-absorbing block, said block being provided with a series of divergent combustion-flues of variable lengths, a heated-air chamber, and means for supplying air to the combustion-flues from said heated-air chamber, as set forth.

55 55 11. The combination of a fire-box, a supplemental combustion-chamber, means for supplying air thereto, and a heat-absorbing block, said block being provided with a series of divergent combustion-flues communicating with the supplemental combustion-chamber, an air-heating chamber and means for supplying air thereto, as set forth.

60 65 12. The combination of a fire-box, a supplemental combustion-chamber, a heat-absorbing block, said block being provided with a cavity on its under side, a series of divergent combustion-flues of variable lengths

communicating with said cavity and the supplemental combustion-chamber, an air-heating chamber, a series of flues connecting the air-heating chamber and the divergent combustion-flues, as set forth.

70 13. The combination of a fire-box, and a heat-absorbing block, said block being provided with a series of divergent combustion-flues of variable lengths, an air-heating chamber located over the combustion-flues and means for supplying air to the combustion-flues from the air-chamber, as set forth.

75 14. The combination of a fire-box, and a heat-absorbing block, said block being provided with a series of divergent combustion-flues an air-heating chamber and means for supplying air to the combustion-flues from the air-chamber, as set forth.

80 85 15. The combination of a fire-box, a supplemental combustion-chamber and a heat-absorbing block, said block being provided with a series of divergent combustion-flues communicating with the supplemental combustion-chamber, and an air-heating chamber, said chamber communicating with the combustion-flues and the supplemental combustion-chamber, as set forth.

90 95 16. The combination of a fire-box, a supplemental combustion-chamber, an air-heating chamber, means for regulating the supply of air to said chamber, and a heat-absorbing block, said block being provided with a series of divergent combustion-flues communicating with the supplemental combustion-chamber, and flues for supplying air to the combustion-flues and the supplemental combustion-chambers simultaneously, as set forth.

100 105 17. The combination of a fire-box, a supplemental combustion-chamber, an air-heating chamber, said chamber communicating with the supplemental combustion-chamber, means for regulating the supply of air thereto, a heat-absorbing block, said block being provided with a cavity on its under side, a series of divergent combustion-flues communicating with the supplemental combustion-chamber, and a series of air-inlet flues for supplying air to the combustion-flues from the air-heating chamber, as set forth.

110 115 18. The combination of a fire-box, a supplemental combustion-chamber, an air-heating chamber, said chamber communicating with the supplemental combustion-chamber, means for regulating the supply of air thereto, a heat-absorbing block, said block being provided with a cavity, a series of divergent combustion-flues of variable lengths communicating with the supplemental combustion-chamber, and a series of air-inlet flues, as set forth.

120 125 19. The combination of a fire-box, a heat-absorbing block, said block being provided with a series of divergent combustion-flues, means for supplying air to said flues, and means for regulating the supply of air, as set forth.

130 20. The combination of a fire-box, and a

heat-absorbing block, said block being provided with a series of curved combustion-flues, as set forth.

21. The combination of a fire-box, and a heat-absorbing block, said block being provided with a series of divergent curved combustion-flues, as set forth.

22. The combination of a fire-box, and a heat-absorbing block, said block being provided with a series of variable divergent curved combustion-flues, as set forth.

23. The combination of a fire-box, and a heat-absorbing block, said block being provided with a heated-air chamber, a cavity, a series of divergent curved combustion-flues, and air-flues connecting the air-chamber and the combustion-flues, as set forth.

24. The combination of a fire-box, and a heat-absorbing block, said block being pro-

vided with a cavity on its under side, a series of divergent combustion-flues of variable lengths communicating with the cavity, and means for supplying air to said flues, as set forth.

25. The combination of a fire-box, a supplemental combustion-chamber, an air-heating chamber having a contracted or tapered exit, said exit communicating with the supplemental combustion-chamber, and a heat-absorbing block, said block being provided with a series of divergent combustion-flues communicating with the supplemental combustion-chamber, and means for supplying air to said combustion-flues, as set forth.
